UNITED STATES PATENT OFFICE.

VICTOR E. STAEBELI, OF BLAINE, WASHINGTON.

TIMEPIECE.

1,176,868.

Specification of Letters Patent. Patented Mar. 28, 1916.

Application filed May 13, 1914. Serial No. 838,385.

To all whom it may concern:

Be it known that I, VICTOR E. STAEBELI, a citizen of the United States, residing at Blaine, in the county of Whatcom and State of Washington, have invented a new and useful Timepiece, of which the following is a specification.

The present invention aims to improve the face construction of an astronomical time piece, so that such a construction may be embodied in a watch without unduly obscuring or complicating the face thereof.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a front elevation of a time piece having the present attachment in use with the zero marks adjacent to the Greenwich meridian time. Fig. 2 is a similar view showing the present attachment in the position it assumes in the locality of eastern time in the United States. Fig. 3 is a cross section through the forward portion of a clock showing the present attachment mounted and by means of which the same may be moved to adjust the meridian time relatively to the time dial. Fig. 4 is a view illustrating a modified arrangement of the present dial. Fig. 5 is an enlarged detail showing the method of placing the numerals by etching or otherwise upon the glass or crystal. Figs. 6 and 7 are perspective views showing the relative positions of the zero points of the scales on the crystal and the markings on the dial which indicate the meridian of reference.

Referring to the drawings, and more particularly to Figs. 1, 2 and 3 thereof, the numeral 1 designates the time piece casing, provided with the usual dial 2, the hour hand 3, and the minute hand 3', the crystal 4 in the present instance being detachably connected for independent rotation or adjustment by means of the clamping band or ring 5 and or be of any desired construction which will permit of the dial or crystal 4 to be adjusted, the purpose of which will presently appear.

The crystal 4 as shown is provided with

the west longitude indication 6 and the east longitude indication 7, the same being arranged concentric of each other with the degree digits progressively increasing from 60 the zero or at the "date line" 8 in opposite directions, this indication therefore including 180 degrees so as to conform to the twelve hour movement of the time piece.

As shown in Fig. 4 or the drawings, the west longitude indication 6' and the east longitude indication 7' is disposed upon the crystal 4' within the time figures of the time dial 2', such crystal 4' being adjustable similar to the crystal 4 heretofore described and being provided with the hour points 9 and 10 opposite the date line 8' so that the same will more readily point to the desired hour when the dial is adjusted.

In describing the use of the present invention, Figs. 1, 2 and 3 will be referred to, the date or zero line of the dial shown in Fig. 1 being disposed at meridian time, or what is commonly known as zero longitude or Greenwich time. The dial as shown in Fig. 2 is set for 75 degrees west longitude or eastern time in the United States, while the dial shown in Fig. 4 is set for 120 degrees west longitude or Pacific time in the United States.

The date lines on the dials in both forms of the invention may be described as markings indicating the meridian of reference.

In setting the respective dials 4 and 4' to correspond with the located standard time or meridian time, the disk is revolved forward until the number corresponding with the designated meridian is directly over and in line with noon or twelve o'clock on the dial of the time piece. The hour hand 3 is therefore the principal indicator and when the clock or watch has been set to standard time for the particular locality or meridian, the same is readily useful and suggestive. The hour hand will then point and show the geographical location of the meridian sun or high noon for every standard time meridian both east and west longitude and for all hours of the day, and also the opposite or midnight meridian. Thus with the clock in the position as shown in Fig. 1, the hour hand pointing to seven o'clock or 105 degrees west longitude, thus indicates what would be the high meridian or noon time at that particular locality, the same also pointing to 75 degrees east longitude, which would indicate the midnight meridian in

this particular locality. By passing to a point diametrically opposite or 15 degrees west longitude, and 165 degrees east longitude, the time of sun setting and sun rising respectively, allowing however for the unequal day and night will be indicated for those particular localities.

In the dial as shown in Fig. 2, the hour and minute hands indicate approximately 10 one forty o'clock while that shown in Fig. 4 indicates ten forty o'clock, so that the structure may be operated by keeping a memorized time location upon the moon, as shown for instance in the "Printed Tide Tables of 15 the United States Department of Commerce, Coast and Geodetic Survey, enumerated Table #6 Moon's Transit and Equation of Time, which shows Greenwich Mean Civil Time of the Moon's Upper and Lower 20 Transits and Equation of the Time," in which this table is compiled for every day throughout the year, it being noted that February 2nd, would show for the locality 120 degrees west longitude that the moon is 25 5 hours and 30 minutes behind or distant from the sun. Thus by keeping a memorized time location on the moon, that is approximately allowing or counting back, that many hours for the moon's distance or meridian location, and whenever shown upon the disk, the two figures upon the disk 4 or 4' will show east and west longitudinal location for high water marks and the opposite 30 two figures will show east and west longitudinal locations for the low water marks or depressions. Taking for illustration, the indication as shown in Fig. 4, and counting back from the hour-hand which is meridian sun five thirty or approximately, and arrive 35 at figures on the dial 4' 15 degrees west and 165 degrees east longitude, the high water mark upon the open sea will be indicated, the opposite numbers across the dial numbered 105 and 75 practically east and west 40 longitude, will indicate the low water mark by the clock dial.

The hour hand indicates the position at all times of the sun, meridian or midnight. We will therefore assume the position of the 50 sun to be at 165 degrees west longitude, the opposite or midnight at 15 degrees east longitude. As the hour hand or time passes on, we arrive at 180 degrees west or east longitude, the opposite or midnight at zero 55 east or west longitude. The hour hand or time passes on, and we arrive at 165 degrees east longitude, which could also be used as 195 degrees west longitude, but as it is never geographically referred to as 195 degrees 60 west longitude, it is therefore 165 degrees east longitude because of the figuring and counting from zero to 180 degrees both east

and west. The position 180 can be read as east or west, if it is assumed to be the meridian sun, then zero east or west is midnight, 65 but as the sun crosses the date line, the same is read east longitude. Upon the disk west longitude is indicated by the top line of figures and east longitude is indicated by the parallel or bottom line of figures. Now if 70 the sun be followed from one revolution that is from zero to 180 degrees and inversely from 180 degrees to zero, one full revolution of 360 degrees is had. Therefore a twelve hour time piece makes two revolutions covering this same period and permits the counting of both east and west at one glance, thus permitting the location of the geographical position of the sun, high noon or midnight, and longitude east or west. 80

Assuming that the time is always set at noon or high meridian at Washington time, the disk is set at 75 degrees west and 105 east longitude to correspond with the twelve o'clock or high meridian. Therefore 75 degrees west longitude is the position of the sun and the opposite 105 degrees east longitude is the midnight meridian. As the time passes, and it arrives at twelve o'clock, the hour hand points to the same figures, but 90 from the position of the longitude dial it is known that the meridian sun is at 105 degrees east longitude and that 75 degrees west longitude is midnight meridian.

It will also be noted that with the present 95 form of dial, that the same may be attached to any form of clock without in any way affecting the hour or minute hand and the time dial.

What is claimed is:

A time piece embodying a dial having a time scale comprising twelve hour characters; and a rotatable crystal housing the dial, the crystal being provided with east and west longitude scales reading in opposite directions from a common zero point by 105 15 degree intervals which are coincident with the hour characters, the time scale and the longitude scales being concentrically disposed, the dial having a marking indicating 110 the meridian of reference, with which marking the zero point may be made to coincide, the space within the innermost of said concentric scales being open and unencumbered 115 to permit a ready cross reference from any marking on one longitude scale to a marking 180 degrees remote therefrom.

In testimony that I claim the foregoing as my own, I have hereto affixed my signature in the presence of two witnesses.

VICTOR E. STAEBELLI.
